Primary Examiner — Paula Allen Greene*(74) Attorney, Agent, or Firm* — Georgi Korobanov(57) **CLAIM**

The ornamental design for an earphones with charging case, as shown and described.

DESCRIPTION

FIG. 1 is a perspective view of a earphones with charging case, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines disclose portions of the earphones with charging case that form no part of the claimed design.

1 Claim, 8 Drawing Sheets(56)
